(57) **CLAIM**

I claim the ornamental design for a LED lamp bezel, as shown and described.

DESCRIPTION

FIG. 1 is a front elevational view of an LED lamp bezel embodying the new design;

FIG. 2 is a front perspective view;

FIG. 3 is a left side elevational view;

FIG. 4 is a rear elevational view; and,

FIG. 5 is a top perspective view.

The broken lines showing the remaining portion of the lamp are included for the purpose of illustration only and form no part of the claimed design.
